UNITED STATES PATENT OFFICE.

CLAUDIUS O. COLLIGNON, OF WESTWOOD, NEW JERSEY.

FOLDING ROCKING-CHAIR.

SPECIFICATION forming part of Letters Patent No. 223,995, dated February 3, 1880.

Application filed January 29, 1879.

To all whom it may concern:

Be it known that I, CLAUDIUS O. COLLIGNON, of Westwood, in the county of Bergen and State of New Jersey, have invented a new and Improved Folding Rocking-Chair; and I do hereby declare that the following is a full, clear, and exact description of the same, reference being had to the accompanying drawings, and to the letters of reference 10 marked thereon, making part of this specification.

This invention is in the nature of an improvement in folding rocking-chairs; and the invention consists in a folding rocking-chair constructed with arms continuous with the front legs, and forming a brace between the rockers and back-posts, to which it is pivoted, and provided with butt-joints, whereby the arms may be folded upward only, in combination with rockers and back-posts and back legs, formed in one continuous piece and pivoted to the rockers, and with a seat pivoted to the front legs, as hereinafter more particularly described.

25 In the accompanying sheet of drawings, Figure 1 is a side view of my chair when in the unfolded position and ready for use, and Fig. 2 a side view of the chair when folded.

Similar letters of reference indicate like parts 30 in both figures.

A A represents the arms of my chair, which are pivoted at their upper ends to the back-posts B at *a*, and extend downward below the seat C, forming the front legs, *b*, which front legs are pivoted to the rockers D at *c*. These arms are divided at *e* *e*, and provided at this point with hinges *f* *f*.

The seat C is pivoted to the front legs, *b*, at *g*, and rests upon a stop, *h*, fixed to the back 40 legs of the chair *k*. These back legs of the chair are likewise pivoted to the rockers D at *l*, and the back legs extend upward continuously and form the back-posts B.

Now, my folding rocking-chair, in this way 45 constructed, when in the proper position for occupancy, will be as shown in Fig. 1, presenting to the eye the appearance of the ordinary non-folding rocking-chair, nothing indicating that it is a folding chair excepting, perhaps, the hinges *f* *f*. When the chair is in 50 this position the frames C of the seat act as braces to keep the chair and its parts rigidly together and firm.

To fold the chair so that it may occupy less 55 space than when open, it is simply necessary

to raise the back of the seat or its frame C from its stop or support *h*, when, by bending the back forward, the chair will at once assume the folded position shown in Fig. 2, in which position it is well adapted for packing, 60 since the shape assumed will admit of the chairs being nested together readily.

If desired to further strengthen the chair when it is opened for use, diagonal braces E may be affixed to the chair by pivoting the 65 rear ends of the braces to the back legs *k* and below the seat, the braces being formed so that when their rear ends are in this way pivoted their front ends, *m*, will abut against the inner sides of the front legs at or near 70 the point at which the seat is pivoted. These front ends, *m*, of the braces are held in position to the front legs by links *n*. The sole purpose of these braces E is to give additional stiffness to the chair when it is opened, if desired; but under ordinary circumstances the 75 seat-frame C will sufficiently brace the chair for use.

If additional strength is wanted, slides or bolts may be affixed to the sides of the arms 80 at the joints *f* *f*, which will stiffen them at those points.

Having now described my invention, what I claim as new, and desire to secure by Letters Patent, is—

1. A folding rocking-chair constructed with the arms A continuous with the front legs, *b*, forming a brace between the rockers and back posts, to which it is pivoted, and provided with butt-joints *f*, whereby the arms 90 may be folded upward only, in combination with the rockers D, a seat, C, pivoted to the front legs, *b*, at *g*, the rear of the seat resting on a stop, *h*, and back posts, B, and back legs, *k*, in one continuous piece, pivoted at *l* to the 95 rockers D, substantially as and for the purpose described.

2. In a folding rocking-chair, pivoted and hinged combined arms and front legs and back-frame and back legs, formed in one piece, 100 in combination with diagonal braces E, pivoted to the back legs, and with their front ends abutting against the inner sides of the front legs, to which they are secured by means of links *n*, substantially as and for the purpose 105 described.

CLAUDIUS O. COLLIGNON.
